UNITED STATES PATENT OFFICE.

GEORGE B. CHADWICK, OF PORTSMOUTH, NEW HAMPSHIRE.

EXPANDING REAMER.

Application filed January 24, 1921. Serial No. 439,414.

To all whom it may concern:

Be it known that I, GEORGE B. CHADWICK, a citizen of the United States, residing at Portsmouth, in the county of Rockingham 5 and State of New Hampshire, have invented new and useful Improvements in Expanding Reamers, of which the following is a specification.

This invention relates to reamers or 10 analogous tools having blades which are capable of simultaneous radial adjustment to vary the effective diameter of the tool.

The object of the invention is to provide certain improvements by which the tool 15 may be used to aline axially spaced apertures, the wall or walls of which are to be cut by the blades, irrespective of whether such apertures have the same or different diameters; by which different groups of 20 blades or other work-engaging members may be adjusted radially independently of each other, and so located as not to weaken the threaded body portion of the tool; and by which other desirable results may be 25 secured. To these ends, my invention consists of a reamer or analogous tool possessing certain structural and other features, as are hereinafter described and particularized in the claims.

On the accompanying drawings,—

Figure 1 represents an expanding reamer embodying my improvements.

Figure 2 represents a longitudinal section through the same.

Figures 3 and 4 respectively represent 30 transverse sections on the lines 3—3, 4—4, of Figure 2.

Figure 5 represents one of the blades.

Figure 6 represents the same kind of 35 reamer but with six blades at the rear and three blades at the front end of the tool.

Figures 7 and 8 represent transverse sections on the lines 7—7, 8—8, of Figure 6.

Figure 9 represents a longitudinal section of the tool in which the guide or sectional bushing members are substituted for the blades at the front end.

Figures 10 and 11 represent cross sections on the line 10—10 of Figure 9 showing different adjustments of the parts.

Figure 12 shows one of the guides or sections of the bushing.

On the drawing, the integral driving mandrel or body 20 is shown as being of unusual length, and as having at its rear

end a non-threaded shank 21 and an angular extremity 22 by which it may be gripped in the chuck of a hand- or power-operated spindle. The remainder of the body may be threaded continuously from the shank 60 21 to the front extremity as indicated at 26, but at 23 I have shown an enlargement which may constitute a unitary part of the body if desired.

The body is provided with two groups of 65 radial, longitudinally-extending slots, in which separate groups of blades or other members may be respectively located for radial adjustment. Each group may consist of any desired number of slots or members, but preferably one group should be in number equal to or a multiple of the other, so that the slots of one group are alined in different longitudinal portions thereof with slots of the other group, for 70 75 reasons to be hereinafter set forth.

In the tool shown in Figures 1 to 4, there are two groups of four slots 24, 25, but, of course, the number of slots may be increased or decreased, as may be permitted 80 by the diameter of the body. The bottom walls of the slots 24 are at the same angle to the axis of the body and are forwardly converging as shown in Figure 2. The slots 25 are alined with the slots 24, but 85 are of greater width, and their rear ends overlap,—as it were,—the front ends of the slots 24. In other words, a slot 24 extends from the point *w* to the point *x*, longitudinally of the body, while the alined slot 90 25 extends from the point *y* to point *z*, so that from *y* to *x*, the narrower slot 24 is formed in the bottom wall of the slot 25. The included angle, between the axis of the body and the bottom of each slot 25, 95 may be equal to, but is preferably greater than, the angle between said axis and the bottom of each slot 24. With the arrangement of slots as shown, the blades or other members placed in one group of slots may be so adjusted as to extend into the transverse zones between *x* and *y*, and yet in said zone there is, to all intents and purposes, only one set of four slots. If the four slots 24 of one group were not alined with the four slots of group 25, there would be eight laterally-spaced slots in the zone *x*—*y*, and the external threads at 26 would be so mutilated or divided as to weaken them.

In the group of slots 24, I place cutting 100 105 110

blades 27, which fit accurately between the parallel side walls thereof, and which are wedge-shaped to fit the bottoms of the slot, so as to present their outer cutting edges 5 28 in parallelism to each other and to the axis of the body. The ends of each blade are beveled as at 29, 30, so that they may be engaged with the beveled end walls 31, 32, on the nuts 33, 34, which are screwed on 10 the threaded body.

In the group of slots 25, I place removable blades or sectional guide or bushing members according to the work to be performed by the tool. For example, in Figures 1 to 4, I have shown a set of blades 35 as located in the slots 25. These, too, are wedge-shaped, but are shown as shorter than the blades 27, though this is not necessary. The beveled ends 36, 37, are engaged 15 with the inwardly beveled end walls 38, 39, of nuts 40, 41, threaded on the body. The members 35 are wider than the slots 24 but fit accurately between the parallel side walls of slots 25, so that, when they project or 20 extend into the zone $x-y$, they are supported by the bottom walls of the said slots from end to end. This would not be the case if the slots 24 and 25 were of the same width, for then the compression of the nut 25 40 would tend to bend the rear ends of the members 35 down into the deeper slots 24 and curve the outer edges of said members. The wedge-shaped members of the two sets are therefore seen to be arranged 30 in pairs end to end within their slots. 35

From the foregoing description, it will be apparent that the members or blades 27 of one group may be radially adjusted to an effective diameter, less than, equal to, or 40 greater than the effective diameter to which the group of members 35 may be adjusted. In Figure 1, for example, I have shown the reamer as operating in two bearing apertures $a b$ in the webs $c d$, so that these two 45 apertures may be reamed in axial alignment. In this case, the effective diameter of the group of blades or members 35 is less than that of the group of members 27. It is evident that in reaming a deep aperture, the blades 27 may be adjusted so as to constitute, practically, extensions of the blades 35, being separated, as they are, only by the length of the two nuts 34, 40; or, if desired, the blades 35 may be so formed as 50 to take roughing cuts and those at 27 to take finishing cuts, so that, by the single reamer, the work may, by one pass of the tool, be both rough-reamed and finished-reamed.

60 In Figures 6 to 8 inclusive, I have shown a reamer like that previously described, except that the rear blades are in number a multiple of the front blades. That is, for example, there are six rear blades 27 and 65 only three front blades 35. In this case,

every alternate slot 24 is alined with a slot 25 and extends into the bottom wall thereof.

In Figures 9 to 12 inclusive, I have shown how sectional bushing or non-cutting guide members 42 may be substituted for the cutting blades in the slots 25. Each member 42 has a longitudinal rib or blade 43 which is wedge-shaped to fit in the slot 25 and which projects radially from said slot. The outer portion of each member consists of a 75 cylindrical segment 44, which projects laterally beyond the rib. The ends of each member are beveled as at 45, 46, to be engaged and held in place by the nuts 40, 41. Preferably the convex outer surfaces of 80 these members are so formed as to be concentric with a cylinder formed about the axis of the body, when they are adjusted radially outwardly to their maximum extent of movement, as shown in Figure 11. 85 Then when they occupy any position nearer the center of the body, each engages the wall of the work at two separate lines of contact, along their outer edges. This I regard as a feature of advantage though it 90 is not essential in every case. The members, which thus constitute a sectional bushing, are used when it is desired to ream, by the use of blades 27, a hole or aperture in axial alignment with the hole in which 95 the bushing members are centered by the walls thereof. Of course, the width of the segmental portions of the members may vary as desired, as will be readily appreciated.

100 A tool may be supplied with both blades 35 and sectional bushing members to be interchangeably applied to the same body, as the nuts 40, 41 fit both. In fact, the nuts 33, 34, 40, 41 may all be identical and 105 interchangeable. They are of short axial length so as to interpose little space, when desired, between the two groups of blades 27, 35, or between a group of blades 27 and the sectional bushing members.

110 The nuts are less in outside diameter than the effective diameter of either the blades or the segmental bushing members, so that they will not engage the walls of the work.

I may call attention to the fact that, when 115 two groups of blades are employed, and adjusted to the same working diameter, the tool may be employed for reaming a long bore or aperture, with better effect than if only one group of long blades were used, 120 first, because the body may be of shorter length for a given radial adjustment of the blades, and, second, because long blades tend to yield or bend laterally and are less effective and accurate in operation than two 125 short alined blades, each of which may be firmly gripped at its ends. It will be understood that, if desired, the segmental bushing members may be located in the slots 24, 130 and blades may be located in the slots 25,

- for reaming a bore or aperture in advance of a bore or aperture in which said bushing members are centered. From one aspect, therefore, the bushing members may be located in either zone of the body, that is, in the zone of the slots 24, or in the zone of the slots 25. I may point out, therefore, that the blades 27 or 35 and the segmental members may be included in the term "radially adjustable work-engaging members," since both perform the identical function of centering the body in the bore or aperture, the walls of which are engaged by said members, whereby the bore or aperture reamed by the blades 27 will be axially aligned with the first-mentioned bore.
- Having thus explained the nature of my invention and described a way of making and using the same, although without attempting to set forth all of the forms in which it may be made or all of the modes of its use, what I claim is:—
1. An expanding reamer comprising an externally threaded body having two groups of longitudinal slots of gradually increasing depth formed therein, the slots of one group being wider than, aligned with, and with their higher ends overlapping the lower ends of the slots in the other group, groups of wedge-shaped members fitting in said groups of slots, and nuts on the threaded body engaging said members for adjusting and securing the respective groups of members in adjusted positions.
  2. An expanding reamer comprising an externally threaded body having two groups of longitudinal slots of gradually increasing depth formed therein, the slots of one group being wider than, aligned with, and with their higher ends overlapping the lower ends of the slots in the other group, groups of wedge-shaped members fitting in said groups of slots, and two pairs of nuts on said threaded body for engaging and adjusting said groups of work-engaging members.
  3. An expanding reamer comprising an externally threaded body, a plurality of radially adjustable blades thereon, and centering means for said body and blades, comprising a group of radially adjustable segmental members having tapering ribs extending therefrom and slidingly seated in complementary longitudinal slots in said body, said members having beveled ends, and nuts on said body having internally tapered ends engaging the tapered ends of said members.
  4. An expanding reamer comprising a body portion having two groups of longitudinal slots of gradually increasing depth formed therein, the slots of one group being wider than, aligned with, and having their higher ends overlapping the lower ends of the slots in the other group, groups of wedge-shaped members fitting in said groups of slots, and means for adjusting said wedge-shaped members axially of said body portion.
  5. An expanding reamer comprising a body portion having longitudinally arranged tapering slots therein, and groups of wedge-shaped members arranged in pairs end to end in said slots and adjustable longitudinally therein through different portions of the lengths of said slots, the lengths through which the members of one group are adjustable overlapping the lengths through which the members of the other groups are adjustable.
  6. An expanding reamer comprising a body portion having longitudinally arranged tapering slots therein, groups of wedge-shaped members arranged in pairs end to end in said slots and adjustable longitudinally therein through different portions of the lengths of said slots, the lengths through which the members of one group are adjustable overlapping the lengths through which the members of the other group are adjustable and means for adjusting said members.
  7. An expanding reamer comprising a body portion having longitudinally arranged tapering slots therein, groups of wedge-shaped members arranged in pairs end to end in said slots and adjustable longitudinally therein through different portions of the lengths of said slots, the lengths through which the members of one group are adjustable overlapping the lengths through which the members of the other group are adjustable and nuts threaded on said body portion and engaging the ends of said members for adjusting said members.
  8. An expanding reamer comprising a body portion having groups of longitudinal slots of gradually increasing depth therein, the higher ends of the slots of one group projecting past the lower ends of the slots of another group, groups of wedge-shaped members fitted in said groups of slots, and means for adjusting said members axially of said body portion.
  9. An expanding reamer comprising a body portion having in different lengthwise portions thereof groups of longitudinal slots of gradually increasing depth the adjacent ends of said slots extending past each other, and groups of wedge-shaped members longitudinally adjustable in said groups of slots.
  10. An expanding reamer comprising a body portion having longitudinally arranged tapering slots therein, and groups of wedge-shaped members arranged in pairs end to end in said slots and independently adjustable longitudinally therein through different portions of the lengths of said slots, the lengths through which the members of

one group are adjustable overlapping the lengths through which the members of the other groups are adjustable.

11. An expanding reamer comprising a body portion having longitudinally arranged tapering slots therein, groups of wedge-shaped members arranged in pairs end to end in said slots and adjustable longitudinally therein through different portions of the lengths of said slots, the lengths through which the members of one group are adjustable overlapping the lengths through which the members of the other group are adjustable, and independent means for adjusting each group of members.
- 10 15
12. An expanding reamer comprising a body portion having groups of longitudinal

slots of gradually increasing depth therein, the higher ends of the slots of one group 20 projecting past the lower ends of the slots of another group, groups of wedge-shaped members fitted in said groups of slots, and means for independently adjusting said members axially of said body portion.

13. An expanding reamer comprising a body portion having in different lengthwise portions thereof groups of longitudinal slots of gradually increasing depth the adjacent ends of said slots extending past each 30 other, and groups of wedge-shaped members independently longitudinally adjustable in said groups of slots.

In testimony whereof I have affixed my signature.

GEORGE B. CHADWICK.
